UNITED STATES PATENT OFFICE

19,612

COATING COMPOSITION

William Koch, Wilmington, Del., assignor to
Hercules Powder Company, Wilmington, Del.,
a corporation of Delaware

No Drawing. Original No. 1,957,786, dated May
8, 1934, Serial No. 626,226, July 29, 1932. Ap-
plication for reissue April 27, 1935, Serial No.
18,691

23 Claims. (Cl. 134—17)

This invention relates to an improvement in
coating compositions and more particularly to
coating compositions which while adaptable for
use generally lend themselves especially for use
5 where a corrosion and abrasion resistant coating
is desired, as for example, various metal sur-
faces, pipes to be buried in the ground, etc.

10 Coating compositions in accordance with this
invention will contain essentially chlorinated
rubber and an ester of abietic acid, as, for ex-
ample, alkyl and aralkyl derivatives. The ester
of abietic acid or rosin as contained in the com-
positions in accordance with this invention may
15 be hydrogenated either by hydrogenation of the
ester or by producing the ester from hydrogenated
abietic acid or rosin.

20 Compositions in accordance with this inven-
tion, in addition to the essential ingredients de-
scribed above, may contain various other ingre-
dients, as, for example, gums, oils, etc. and will
contain a suitable solvent or solvent mixture to
25 give to the compositions desired viscosity or
fluidity to enable their application, as for exam-
ple, by spraying, brushing, dipping or otherwise,
as may be desired.

30 The chlorinated rubber comprising one of the
essential ingredients of coating compositions in
accordance with this invention may be either
chlorinated raw rubber or chlorinated vulcan-
ized rubber, or mixtures thereof, both being con-
templated as within the term "chlorinated rubber"
35 as used herein. While the chlorinated rubber
will preferably have a relatively high per-
centage of chlorine, say above 67%, it will be
understood that rubber containing any substan-
tial percentage of chlorine, say as low as 50%,
will be usable.

40 The chlorinated rubber, either raw or vulcan-
ized, may be obtained from any source, or may
be produced in any suitable manner. Thus, for
example, suitable chlorinated rubber may be
produced from raw or vulcanized rubber by dis-
solving the rubber in a solvent, as carbon tetrachloride,
45 which will be unaffected by chlorine, heating the solution to a temperature within the
range 80—110° C. and introducing chlorine into the
heated solution. Where vulcanized rubber
is treated the sulphur will be separated out by
the chlorine, appearing as a chloride of sulphur,
50 all, as for example, is more fully disclosed in
U. S. Patent No. 1,852,043 to Deseniss and Nielson.

55 Other methods for the production of suitably
chlorinated rubber are disclosed, for example,
in the United States patents to Carlton Ellis No.
1,544,530 and No. 1,544,529, to Peachey No.

1,234,381 and to Deseniss and Nielson No. 1,852,-
043. It will, of course, be understood that suit-
ably chlorinated rubber for use in connection
with this invention may be produced in any de-
sired manner, the references made herein being 5
for illustrative purposes only.

Various esters of abietic acid or rosin may be
used in the composition in accordance with this
invention, as for example, ethyl abietate, methyl
abietate, propyl abietate, benzyl abietate, etc. 10
etc. Abietic acid or rosin esters as used may be
hydrogenated as has been indicated, and it
will be understood that with reference to such
esters in the description of compositions in ac-
cordance with this invention heretofore and as 15
used in the claims appended hereto, by the term
"abietic acid or rosin ester" such esters, either
hydrogenated or not hydrogenated, is contem-
plated.

20 As has been indicated, various ingredients in
addition to those indicated above as essential
may be included in compositions in accordance
with this invention, as for example, oils, as lin-
seed oil, China wood oil, etc., etc., gums or resins,
25 as ester gum, coumarone, phenol-formaldehyde
condensation resins etc., pigments and other in-
gredients which may be desirable and which are
compatible with the essential ingredients, chlor-
inated rubber and abietic acid or resin ester.

30 Any suitable solvent or solvent mixture may be
used in the preparation of solvent mixtures in ac-
cordance with this invention and, for example, a
mixture of xylol and toluol, ethylene dichloride,
monoalkylated ether of ethylene glycol, ethyl
acetate, etc., may be used.

35 In the formation of compositions in accordance
with this invention the essential ingredients may
be used in widely varying proportions and other
ingredients which may be included may likewise
be included in widely varying proportions. 40

For illustration, for example, chlorinated rubber
may be used in amount within say about the
range 10—40%, while an abietic acid or resin acid
ester may be included within say about the range 45
2—20%. The solvent or solvent mixture may be
used in any desired amount with consideration
for the viscosity or fluidity desired for the com-
position. Thus, for example, the solvent or sol-
vent mixture may be in amount within say about 50
the range 85—40%, to give compositions which
may be readily applied as by brushing, spraying,
dipping or the like.

55 As illustrative of the practical adaptation of
this invention, for example, satisfactory compo-

sitions for various uses may be made up on the following formulæ:

15 It will be understood that abietic acid or resin ester, as methyl abietate which has not been hydrogenated, may be substituted for hydrogenated methyl abietate given in the above formulæ.

The composition in accordance with the above formulae will be found desirable for various uses and will be found especially desirable where a corrosion resistant coating is desired. As will be appreciated, the formulations given above for purposes of illustration may be widely varied depending upon the particular uses for which they are intended within the scope of this invention.

25 As has been indicated, the compositions in accordance with this invention may be applied to various surfaces such as wood, metal and the like, by spraying, brushing, dipping, etc., and on evaporation of the volatile ingredients will form a coating having excellent adherence to the surface, of desirable appearance, flexibility, etc., etc., and a very high resistance to corrosion.

What I claim and desire to protect by Letters Patent is:

35 Patent No. 3,330,621
1. A coating composition including chlorinated rubber and an abietic acid ester of the group alkyl and aralkyl esters and a solvent.

40 2. A coating composition including chlorinated-rubber and a hydrogenated abietic acid ester of the group alkyl and aralkyl esters and a solvent.

3. A coating composition including chlorinated rubber and an abietic acid ester of the group alkyl and aralkyl esters, a resin and a solvent.

45 4. A coating composition including chlorinated rubber and an abietic acid ester of the group alkyl and aralkyl esters, a drying oil and a solvent.

50 5. A coating composition including chlorinated rubber and an abietic acid ester of the group alkyl and aralkyl esters, a resin, a drying oil and a solvent.

6. A coating composition including chlorinated rubber about 10-40% and an abietic acid ester about 2-20% of the group alkyl and aralkyl esters

7. A coating composition including chlorinated

rubber about 20% and an abietic acid ester about

2-6% of the group alkyl and aralkyl esters and a solvent.

8. A coating composition including chlorinated rubber about 20% and an abietic acid ester about 2-6% of the group alkyl and aralkyl esters and a solvent about 80%. 5

9. In combination a surface and a film containing chlorinated rubber and an abietic acid ester of the group alkyl and aralkyl esters adhered to and supported on said surface. 10

10. In combination a surface and a film containing chlorinated rubber and a hydrogenated abietic acid ester of the group alkyl and aralkyl esters adhered to and supported on said surface.

11. In combination a metal surface and a film containing chlorinated rubber and an abietic acid ester of the group alkyl and aralkyl adhered to and supported on said surface. 15

12. A composition including chlorinated rubber and an abietic acid ester of the group alkyl and aralkyl esters.

13. A composition including chlorinated rubber and a hydrogenated abietic acid ester of the group alkyl and aralkyl esters.

14. A composition including chlorinated rubber, an abietic acid ester of the group alkyl and aralkyl esters and a resin. 25

15. A composition including chlorinated rubber, an abietic acid ester of the group alkyl and aralkyl esters, a resin and a drying oil. 30

16. A composition including chlorinated rubber, an abietic acid ester of the group alkyl and aralkyl esters, a resin and linseed oil.

17. A composition including chlorinated rubber within the range about 10%-40% and an abietic acid ester of the group alkyl and aralkyl esters within the range about 2%-20%. 35

18. A composition including chlorinated rubber, a hydrogenated abietic acid ester of the group alkyl and aralkyl esters, a resin and a drying oil. 40

19. A composition including chlorinated rubber, an abietic acid ester of the group alkyl and aralkyl esters, and a softening agent for the chlorinated rubber.

20. A composition including chlorinated rubber, an abietic acid ester of the group alkyl and aralkyl esters and China-wood oil. 41

21. A composition including chlorinated rubber, an abietic acid ester of the group alkyl and aralkyl esters, and boiled China-wood oil. 50

22. A composition including chlorinated rubber, an abietic acid ester of the group alkyl and aralkyl esters, China-wood oil and ester gum.

23. A composition including chlorinated rubber, an abietic acid ester of the group alkyl and aralkyl esters, and ester gum. 5

WILLIAM KOCH.
